(57) CLAIM

The ornamental design for a wash cloth with soap pocket, as shown and described.

DESCRIPTION

FIG. 1 is a perspective view of the wash cloth with soap pocket of my new design.

FIG. 2 is an exploded perspective view thereof.

FIG. 3 is a top plan view thereof.

FIG. 4 is a bottom plan view thereof.

FIG. 5 is an enlarged elevational view of the front edge thereof.

FIG. 6 is an enlarged elevational view of the rear edge thereof.

FIG. 7 is an enlarged elevational view of the left end thereof; and,

FIG. 8 is an enlarged elevational view of the right end thereof. The broken line figure shown in FIG. 2, depicting a bar of soap, is an environmental element, and forms no part of my new design.
